United States Patent

Des. 239,035
Patented Mar. 2, 1976

239,035

LOUDSPEAKER ENCLOSURE

Charles A. Ross, Fort Scott, Kans., assignor to
Road Electronics, Inc., Fort Scott, Kans.

Filed Dec. 16, 1974, Ser. No. 533,007

Term of patent 14 years

Int. Cl. D14—01

U.S. Cl. D26—14 G

The rear and undisclosed side of the loudspeaker enclosure are substantially plain and unornamented.

I claim:

The ornamental design for a loudspeaker enclosure, as shown and described.
